ARTHUR T. YATES, OF BUFFALO, NEW YORK, ASSIGNOR TO BUFFALO FORGE COMPANY,
OF BUFFALO, NEW YORK

BENDING MACHINE

Application filed October 3, 1927. Serial No. 223,599.

This invention relates to machines for bending bars, rods, tubes or the like by passing the same lengthwise between rolls.

The objects of this invention are to provide an attachment whereby a bending machine can be adapted to make bends of shorter radii than those which the machine without the attachment is capable of making, and thus considerably increase the scope of work which the machine is capable of doing; also to provide an attachment of this kind in which a small idler roll is mounted on the revolving shaft of the upper roll usually provided on the machine; also to provide means for mounting the bending roll outwardly beyond the ends of the driving shafts of the bending machine so that these shafts will not interfere with the bending of the work about a small radius; also to improve the construction of machines of this kind in other respects hereinafter specified.

In the accompanying drawings,

Fig. 1 is an end elevation of a bending machine having my attachment secured thereto.

Fig. 2 is a fragmentary, top plan view thereof on an enlarged scale.

Fig. 3 is a fragmentary, side elevation of the end portion of the machine.

Fig. 4 is a fragmentary, sectional elevation thereof, on line 4—4, Fig. 1.

Fig. 5 is a fragmentary, end elevation thereof, showing the machine bending a piece of work on a small radius.

Fig. 6 is a sectional elevation thereof on line 6—6, Fig. 5, with the idler roll raised.

Fig. 7 is a side elevation of the several parts comprising the lower roll and its mounting on the machine, the several parts being shown detached from each other.

The bending machine with which my attachment is adapted to cooperate may be of any suitable or desired construction, and in the accompanying drawings only portions of a bending machine of this kind are shown. 10 represents the frame of this machine on which two driven shafts 11 and 12 are mounted which usually support a pair of bending rolls (not shown). The driven shaft 14 of the third bending roll is mounted on a piv-

oted member 15 which is journalled at 16 on the frame of the machine in such a manner that the third roll may be adjusted toward and from the space between the two lower bending rolls. The adjustment of the pivoted member 15 in the machine shown is effected by means of a threaded nut 18 cooperating with a screw threaded bolt or member 19, the lower end of which is fixed in the frame 10 of the machine. 20 represents the ratchet lever for turning the nut 18, and 21 represents a hand wheel which may be secured to or formed integral with the nut and which can be used for turning this nut. 17 represents a lever pivoted on a fixed part of the machine and having a counterweight 23 arranged on the outer portion thereof, the inner end of the lever acting on the bearing of the third roll shaft 14 in any suitable manner (not shown) to counterbalance the weight of the third roll and its shaft. X represents the work to be bent which is passed between the rolls in either direction depending upon the direction of rotation of the rolls, which is controlled by means of a clutch lever 22 and suitable driving mechanism, not shown. 24 represents guide rollers, rotatable about inclined axes for guiding the work passing to and from the bending rolls. Each of the three drive shafts 11, 12 and 14 is provided in its end with a central aperture 25, adapted to receive a threaded stud 26 by means of which the bending rolls may be secured to the ends of the driving shafts, and these shafts are also provided with keyways 27 for holding the usual bending rolls against turning relatively to the shafts. All of these parts thus far referred to have heretofore been used in connection with bending machines and of themselves constitute no part 80 of this invention.

With the bending machine as described, as ordinarily used, the bending is done about the ends of the shafts 11, 12 and 14. In accordance with my invention, when my improved attachment is applied to the bending machine, the bending is done beyond the ends of the shafts, and consequently the work can be bent on radii smaller than would be possible if the bending were to be effected about 95 100

the ends of the shafts. The bending rolls of my attachment used in connection with the two lower shafts 11 and 12 are arranged substantially concentric with the axes of these shafts, while the upper bending roll is positioned eccentrically with reference to the upper shaft 14.

Any suitable means may be employed for attaching the lower bending rolls to the shafts 11 and 12 concentric with the axes thereof and beyond the ends of these shafts. In the particular construction shown this is effected by providing an adapter or sleeve for each of the two shafts 11 and 12, each adapter including a cylindrical sleeve portion 30 provided with a keyway 31 adapted to register with the keyway 27 in the shaft, a suitable key being inserted into the two keyways to hold the sleeve and shaft against relative rotary motion. The sleeve portion 30 fits over the end of the shaft and is provided with an integral cylindrical extension 32 extending beyond the end of the shaft, the outer cylindrical face of which is also provided with a keyway 33. The cylindrical extension 32 is formed to receive a bending roll 35 having a peripheral portion 36 which may be of any suitable shape depending upon the shape of the work to be bent, a half round groove being provided in the bending roll shown to bend work of circular cross section, such, for example, as a tube or rod. The inner face of this roll is adapted to fit over the periphery of the extension 32 of the adapter or sleeve and a keyway 37 is provided on this inner face which is adapted to be placed in registration with the keyway 33 on the adapter and a suitable key 39 may be inserted into the two keyways to hold the roll 35 from turning relatively to the adapter. Each lower roll and its sleeve or adapter is held against endwise displacement on its shaft by means of a nut 40 having an internally threaded portion 41 adapted to engage with the stud 45 26, and a flange 43 which engages the bending roll and holds the same on the cylindrical portion 32 of the adapter between the flange 43 of the nut and a flange 44 on the adapter. The outer end of the nut is provided with any suitable means for turning the same, such, for example, as a cylindrical flange 45 provided with apertures 46 through which a bar or rod may be inserted for turning the nut. By means of this construction the two lower bending rolls may be rigidly secured on the lower shafts 11 and 12 in such a manner as to extend beyond the ends of these shafts. It is obvious that other means for securing these rolls on the shafts may be employed, if desired.

50 represents the upper bending roll which is provided with a face 51 corresponding to the peripheral faces of the lower two rolls. This upper bending roll is preferably journaled to rotate freely about a stud or pro-

jection 52 of a bracket 53, the bearing roll being held on the stud or projection by means of a disk 54, the edge portions of which engage the bending roll and which is secured to the bearing projection 52 by means of a set screw 55 or other means. The bracket 53 is suitably mounted on the pivoted member 15 of the frame in such a manner as to move up and down when the frame 15 is swung about its pivot 16, and preferably the bracket is journaled on the end of the driving shaft 14. For this purpose, in the construction shown, the bracket is provided with a cylindrical bore 57 into which the end of the shaft 14 extends and within which this shaft is freely rotatable. In order to form a good bearing between the driven shaft 14 and the bracket 53, a bearing sleeve 58 is preferably secured to the end of the drive shaft 14 to rotate with the drive shaft. The bracket 53 may be held against endwise displacement on the shaft 14 in any suitable manner, for example, by means of a set screw 60 which extends through an arc shaped slot 61 in a peripheral portion of the bracket 53 and the end of which screw is secured in a threaded hole in the adjustable member 15 of the bending machine.

In order to hold the bracket and the bending roll 50 thereon in correct relation to the other bending rolls, a sliding connection is preferably provided between the bracket and the frame member 10, which connection permits vertical adjustment of the bracket 53 and the upper bending roll 50 mounted thereon. This sliding connection in the particular construction shown includes an undercut slot 62 formed in the frame member 10 and in which the head of a bolt 65 may move vertically. This bolt also passes through a hole in the lower portion of a downwardly extending arm 66 of the bracket 53, the bolt being held in place by a nut 67 or other suitable means.

As a result of the construction described, the bracket 53 carrying the upper bending roll is adjustable up and down when the pivoted adjusting member 15 is moved up and down about its pivot. Downward pressure is exerted upon the bracket through the upper driving shaft 14 which bears the cylindrical bearing recess formed in the bracket 53 and consequently transmits no rotary motion to this bracket. Because of the location of the upper bending roll 50 below the axis of the shaft 14, it is possible to make this roll of smaller diameter than would be possible if the roll were mounted on the shaft 14, and consequently it is also possible to move this bending roll downwardly to a greater extent into the space between the two lower bending rolls, and this results in rendering the machine capable of bending the work about much smaller radii than would be possible without this attachment. Consequently by means of my attachment it is possible to

utilize the bending machine for a greater variety of work. When it is desired to use the machine for heavier work, the parts of my improved attachment can be readily removed from the machine and the usual bending rolls substituted therefor.

By arranging the bending rolls of my attachment beyond the ends of the roll shafts, in addition to making it possible to bend work about shorter radii than would be possible without the attachment, another advantage results, namely that in bending tubes or rods into coils, the coils can be gradually reduced in diameter by passing the same alternately in opposite directions between the rolls, by reversing the direction of rotation of the rolls. By arranging the bending rolls beyond the roll shafts, the bending rolls are far enough from the frame of the machine to permit the coils to be passed into the space between the upper and the two lower roll shafts.

I claim as my invention:—

1. The combination with a bending machine having three substantially parallel shafts, one of which is adjustable toward and from the space between the other two shafts, of a bracket mounted on said adjustable shaft and held against rotating about the axis of said adjustable shaft and having a bending roll mounted thereon, and bending rolls on said other two shafts adapted to be driven and to cooperate with said first mentioned bending roll.

2. The combination with a bending machine having three substantially parallel shafts, one of which is adjustable toward and from the space between the other two shafts, of a bracket mounted on said machine which is movable with said adjustable shaft toward and from said space between said other two shafts, a bending roll mounted on said bracket, and bending rolls on said other two shafts which are driven for cooperation with said first mentioned bending roll.

3. The combination with a bending machine having three substantially parallel shafts, one of which is adjustable toward and from the space between the other two shafts, of a bracket mounted on said machine which is movable with said adjustable shaft toward and from said space between said other two shafts, a bending roll mounted on said bracket and extending beyond the end of said shaft, and bending rolls mounted on said other two shafts and extending beyond the ends thereof and driven for cooperation with said first mentioned bending roll.

4. An attachment for a three roll bending machine having three substantially parallel roll shafts, and a member on which one of said shafts is mounted and which is adjustable toward and from the space between said other two shafts, said attachment including a bracket mounted on said adjustable mem-

ber, a bending roll journalled on said bracket and adapted to cooperate with driven rolls mounted on said other shaft.

5. The combination of a bending machine having a stationary frame, a pair of driven shafts journalled on said frame, a member movably mounted on said frame, and a shaft journalled in said member and adjustable toward and from the space between said other two shafts, a bracket mounted on said movable member and having a portion which has a sliding connection with said stationary frame, a bending roll mounted on said bracket, and a pair of rolls mounted on said two shafts with which said first mentioned bending roll is adapted to cooperate, said sliding connection between said bracket and said stationary frame member serving to guide said first mentioned bending roll into correct relation to the space between said other two bending rolls.

6. An attachment for a three roll bending machine having a pair of roll shafts journalled in a fixed frame and a third roll shaft journalled on a member adjustably mounted on said frame, said attachment including a bracket mounted on said adjustable member and a roll mounted on said bracket and pivoted beyond the end of said third roll shaft, sleeves mounted on said pair of roll shafts, and rolls mounted on said sleeves beyond the ends of said shafts and adapted to cooperate with said roll on said bracket.

7. An attachment for a three roll bending machine having a pair of roll shafts journalled in a fixed frame and a third roll shaft journalled on a member adjustably mounted on said frame, said attachment including a bracket mounted on said adjustable member and a roll mounted on said bracket and pivoted beyond the end of said third roll shaft, sleeves mounted on said pair of roll shafts and extending beyond said shafts, rolls adapted to be mounted on said sleeves beyond said shafts, and a clamping device for engaging each of said pair of roll shafts and securing said rolls and said sleeves on said shafts.

8. An attachment for a three roll bending machine having a pair of roll shafts journalled in a fixed frame and a third roll shaft journalled on a member adjustably mounted on said frame, said attachment including a bracket having a bearing recess formed therein in which the end of said third roll shaft may rotate, rolls mounted on said pair of roll shafts, a roll mounted on said bracket and adapted to cooperate with said first mentioned rolls, and a slid able connection between said bracket and said fixed frame to guide said roll on said bracket into correct relation to the first mentioned rolls.

9. An attachment for a three roll bending machine having a pair of roll shafts journalled in a fixed frame and a third roll shaft journalled on a member adjustably mounted

- on said frame, said attachment including a bracket having a bearing recess formed therein in which the end of said third roll shaft may rotate, rolls mounted on said pair of roll shafts, a roll mounted on said bracket and adapted to cooperate with said first mentioned rolls, a slideable connection between said bracket and said fixed frame to guide said roll on said bracket into correct relation to said first mentioned rolls, and a connection between said bracket and said adjustable member for holding said bracket on said third shaft and for permitting movement of said bracket relatively to said adjustable member.
10. An attachment for a three roll bending machine having a pair of roll shafts journalled in a fixed frame and a member adjustably mounted on said frame and on which a third roll shaft is journalled, said attachment including a bracket having a bearing recess therein into which the end of said third roll shaft is adapted to enter and in which said shaft may revolve, releasable means for holding said bracket against endwise movement relatively to said third roll shaft, a sliding connection between said bracket and said fixed frame, a roll journalled on said bracket, and a pair of rolls mounted on said other two roll shafts, said sliding connection guiding said roll on said bracket into and out of operative relation to said other two rolls.
11. An attachment for a three roll bending machine having a pair of roll shafts journalled in a fixed frame and a member adjustably mounted on said frame and on which a third roll shaft is journalled, said attachment including a bracket having a bearing recess therein into which the end of said third roll shaft is adapted to enter and in which said shaft may revolve, releasable means for holding said bracket against endwise movement relatively to said third roll shaft, a sliding connection between said bracket and said fixed frame, a roll journalled on said bracket and arranged beyond the end of said third shaft, and a roll mounted on each of said pair of roll shafts and arranged beyond the ends thereof, said slideable connections guiding said roll on said bracket into correct relation to said rolls on said other two shafts for effecting bending of the material beyond the ends of said roll shafts.
